BOTTLE BLOWING MACHINE

Harry P. Cox, Jr., Lancaster, Pa., assignor to
 Armstrong Cork Company, Lancaster, Pa., a
 corporation of Pennsylvania

Application January 25, 1943, Serial No. 473,444

15 Claims. (Cl. 49—18)

This invention relates to bottle blowing machines and is concerned primarily with a mechanism by which parisons which have a choke or constriction in the neck as they are delivered to the blow mold from the blank mold are not blown into bottles and may be readily distinguished and rejected.

In the manufacture of bottles, such as those commonly used in packaging beverages, for example, the charge of glass is fed to a blank or parison mold where the neck ring and inner plunger form the so-called "finish" and "corkage" of the bottle, respectively, and the blowing is commenced but not completed. The parison of glass is then transferred to a blow mold where final forming of the bottle is accomplished by blowing.

One defect occurring on occasion is the formation of a constriction of the interior of the neck immediately below the inner neck plunger. This constriction is commonly termed a "choke" and generally results from insufficient or improper corkage reheat before counter blowing. Any choke of major size is objectionable because it prevents the filling tube of the filling machine used by the beverage bottler from properly entering the bottle neck with the result that the filling mechanism is broken or damaged. When the filling mechanism is broken, the entire filling line must be shut down until repair is made and thus one bottle with a choke is disastrous. Modern filling methods require rapid flow of liquid into the bottle and as a consequence the filling tubes are generally only slightly smaller in outer diameter than the inner diameter of the bottle neck, only sufficient tolerance being allowed to permit ready insertion and removal of the filling tube and escape of air during filling. It is always a cause of serious complaint if bottles are delivered to the beverage bottler with choke necks.

Internal constrictions or chokes are not readily detected in the usual visual inspection of the bottle and as a result a plug gauge must be inserted into the bottle necks to determine if any chokes are present. This is an expensive hand inspection and is burdensome to the glass manufacturer. In addition, it is possible for an inspector to fail to insert the plug gauge and there is no way of satisfactorily determining if any given bottle has been inspected. Since this defect may occur only at rather infrequent intervals, there is some tendency of the inspectors to be lax in inserting the plug gauge in each bottle. Any single bottle supplied to the bottler with an objectionable choke will cause damage to the filling machine and result in loss of production.

The main object of this invention is to provide a device which will automatically detect any objectionable choke in a neck of a parison after it is delivered from the blank mold and is in position in the blow mold and which is effective for controlling the supply of air for blowing the parison into a bottle so that if there be a choke in the neck of the parison a bottle will not be blown. Those parisons which are not blown may be readily distinguished by a casual glance of the inspector or may be discarded by the machine itself or by the machine operator. The necessity for gauging each bottle during final inspection is eliminated.

According to one embodiment of the invention, the blow mold is provided with a gauge which is free to enter the neck of a properly formed parison but which will be displaced by engagement with a choke in the neck of the parison, the final blow air supply to the blow mold being controlled by the position assumed by the gauge when inserted in the neck of the parison. In the preferred embodiment, the gauge is so constructed that the final blow air will pass through an opening in the gauge when the gauge enters a properly formed neck, the air passing into the parison and being effective to blow the parison disposed in the blow mold. When the gauge is displaced by a choke in the neck the blow air is by-passed through an appropriate opening or openings to the atmosphere and no blowing of the parison into a bottle is accomplished. In another embodiment, the gauge is effective for initiating an electrical device which is effective for controlling the supply of air to the blow mold, no air being supplied when the gauge is displaced by engagement with a choke in the neck of the parison which is disposed in the blow mold.

In order that the invention may be more readily understood, it will be described in connection with the accompanying drawing which illustrates the two embodiments referred to generally above and in which

Figure 1 is a sectional view of a portion of a blow mold and blow head arrangement of conventional form with the mechanism of my invention incorporated as a part thereof, the view showing the gauge in position within a parison having a properly formed neck;

Figure 2 is a similar view showing the gauge in elevated position by reason of engagement with a choke in the neck; and

Figures 3 and 4 are views similar to Figures 1 and 2 showing a modified arrangement for electrical control of the blow air.

In the views selected for illustration, a Hartford-Empire I. S. machine blow mold and blow head arrangement is shown. The invention is not limited to any particular type or style of blow mold or blow head arrangement and may be embodied in blowing machines of a wide diversity of types.

In Figure 1 a minor portion only of a blow mold 2 is shown. The blow mold may be any one of a number of forms. It is in this mold that the parison 3 which has been delivered from a blank mold is blown into a bottle of the desired final shape. The parison of glass as delivered from the blank mold to the blow mold has a finish and corkage which is substantially completely formed. For convenience this will be referred to as a substantially completely formed neck finish. It will be understood that some slight formation of the neck may be accomplished in the final blowing but for all general purposes the neck finish is substantially completely formed as the parison is delivered to the blow mold. It will be noted that the neck 4 of the parison in the blow mold of Figure 1 has a substantially smooth cylindrical inner neck surface 5. This is the desired shape and indicates that a proper counter blow has been effected in the blank mold.

Disposed above the blow mold 2 is a blow head 6 which is carried by a blow head holder 7 which connects to the blow head 6 by means of a bayonet joint arrangement 8. A blow head arm 9 is effective for bringing the blow head and its associated mechanism into position when the parison 3 is properly disposed in the blow mold 2. The blow head 6 and the blow head holder 7 are provided with openings through which a tube 10 is free to pass. The tube 10 is provided with a gauging end 11 of appropriate size, depending upon the size of the standard filling tube used in filling the bottle being produced. The allowable tolerances vary to some extent depending upon the type of closure which will be used to seal the bottle, upon the thickness of the wall of glass at the neck, and other variable factors. The gauging end 11 is so proportioned that it will pass freely into a properly formed parison but will engage any objectionable constriction or choke in the parison neck. In Figure 1, a gauging end 11 is shown in a parison having a properly formed neck. The tube 10 is provided with a central opening 12 which is the embodiment shown in Figure 1 extends throughout the length of the tube but which may be formed as shown in Figures 3 and 4 which will be more completely described later. A cylinder head 13 is fastened to the blow head arm 9 by bolts 14 and the tube 10 is provided with a piston head 15 movable within the bore of the cylinder head 13. An annular recess 16 is provided in the piston head 15 terminating in the shoulder 17 which limits downward movement of the tube 10 by engagement with the top of the blow head shoulder 7. The space from the top of the piston 15 to the recess 16 is relatively narrow so that any minor displacement of the tube 10 in an upward direction will bring the recess 16 into a position above the inlet opening 18 through which final blow air is supplied from a source S. The air normally enters the bore of the cylinder head 13 above the top of the piston 15 when the tube 10 is in its lowermost position. The direction of travel of the final blow air is shown in Figure 1 by a series of arrows. This blow air is effective for forming the parison into a bottle of the desired final shape.

Referring now to Figure 2, it will be noted that the parison 3 has a choke 19 indicating that insufficient or improper corkage reheating has been accomplished before counter blowing. This choke 19 is of such size as to be objectionable although its presence might go undetected by the usual visual inspection. When the blow head 6 is brought into position over the blow mold 2 with the parison 3 of Figure 2 in position, the 10 gauging end 11 will come into contact with the choke 19 and the piston 15 will be elevated to a position above the inlet tube 18. The formation of the piston 15 and the recess 16 is such that the blow air will be effective for lifting the piston 15 to its uppermost position. For sake of clarity of illustration, the piston 15 is shown in a slightly lowered position in Figure 2 with the gauging end 11 lying in engagement with the choke 19. In actual operation the pressure 15 of the final blow air will normally be sufficient to elevate the piston 15 to its uppermost position. Movement of the piston 15 to a point above the inlet opening 18 by engagement of the gauging end 11 with the choke 19 will result in the 20 final blow air continuing the elevation of the piston 15 to that position. The final blow air entering through the inlet 18 is now not free to pass into the blow head since the opening thereinto is in the top of the piston 15 which is now elevated above the inlet 18. Suitable exhaust ports 20 are provided whereby the final blow air is dispersed in the atmosphere as shown by the arrows in Figure 2.

The modification shown in Figures 3 and 4 is generally similar to that shown in Figures 1 and 2 and corresponding numbers have been applied to the corresponding parts. There are two important differences between the two showings. The primary difference is in the air control arrangement. In the embodiment shown in Figures 3 and 4, control is electrically effected by means of a solenoid valve 21 which is effective for interrupting the supply of final blow air to the blow head. Current is fed from a source C by wires 22 and 23, the wire 22 being grounded to the cylinder head 13 by a binding post 24. A contact 25 is carried by the piston 15 and, when the piston is in its lowermost position, the gauging end 11 of the tube 10 passing freely through the properly formed neck 5 of the parison 3 of Figure 3, the contact 25 will come in engagement with a metal contact strip 26 insulated from the machine by strips of insulation 27 and 28. The solenoid valve is connected to the contact strip 26 by a wire 29 and a binding post 30. The other side of the solenoid 21 is connected directly to the source of current C by the wire 23.

When the contact 25 is in engagement with the contact strip 26 as shown in Figure 3, current is supplied to the solenoid 21 from the source C and the solenoid valve is opened to permit the entrance of final blow air into the inlet tube 18 and thence into the blow head. When the gauging end 11 comes into contact with a choke 19, as illustrated in Figure 4, the contact 25 will be elevated away from the contact strip 26 and the supply of current to solenoid valve 21 will be interrupted.

The operation of all of the devices shown in the drawing is essentially the same; namely, when a choke is encountered in a parison as delivered to the blow mold from the blank control means are effective for preventing the entrance of final blow air into the blow head.

While in Figures 3 and 4 the control valve is

shown as the normally closed and electrically opened type, a reverse arrangement may be provided by means of which the valve is closed when the gauging end 11 engages a choke 19, the valve being normally open.

The second difference between the showings of Figures 1 and 2 and 3 and 4 is in the direction of the final blow air. In Figures 3 and 4, the opening 12 in the tube 10 which connects the source of final blow air with the blow head does not extend throughout the length of the tube 10. In this modification, a plurality of openings 31 are provided immediately above the neck of the bottle so that the air which is effective for finally forming the parison into a bottle must flow downwardly along the neck thereof and past the gauging end 11, thus tending to smooth out any minor constriction which might be present. It has been found that with the arrangement shown in Figure 1 there is some tendency for the air which is directed through the passage 12 into the bottle below the upper end of the neck to sharply accentuate any minor choke which may be present in a small-neck bottle. This is caused by the air which moves upwardly along the outer surface of the gauging end 11. With the arrangement shown in Figures 1 and 2, the air is directed downwardly along the neck and since the body of glass is more plastic in the lower areas spaced from the bottle lip, any minor constriction will be flowed out. With most bottles, the arrangement shown in either of the embodiments may be used with success, but if there is any tendency for the accentuation of small chokes, this may be completely eliminated by using the tube arrangement of Figure 3.

Both of the embodiments illustrated are fully automatic and are relatively simple and positive in operation so as to require little or no adjustment or maintenance. A parison which is defective because of a choke neck will not be blown to a bottle and may be discarded by the machine itself. Such unblown parisons are readily distinguishable as they are delivered from the blow mold and may be discarded by the operator or by the inspector. As a matter of fact, most unblown parisons will be of such misshapen form that they will not even stand upright on a lehr conveyor. An additional advantage flowing from the use of this invention is that the blowing machine operator will be immediately informed of any failure to properly reheat the corkage. When unblown parisons are delivered from the blow mold the operator will know that the machine is not functioning properly and is producing parisons with choked necks. Adjustment can then be made and the difficulty eliminated. With the present devices the existence of choke necks is not detected until final inspection and this occurs many hours after initial forming with the result that many choke necked bottles may be produced before the operator is aware of the fact that the machine is not forming satisfactory parisons. While the gauging end may be elevated in some instances by chokes which would under normal circumstances be blown out in the final blowing operation, the notice to the operator that even minor chokes are occurring, is more than adequate compensation for the few bottles which may be lost and there is the positive assurance that the finally blown bottles will not have choked necks.

While certain embodiments of the invention have been illustrated and described, it will be understood that the invention is not limited to such

embodiments which were selected for purposes of illustration only but may be otherwise embodied and practiced within the scope of the following claims.

I claim:

1. In a bottle blowing machine, the combination of a blow mold in which a parison of glass with a substantially completely formed neck finish is received for final blowing, a gauge movable to a position within the neck of a parison received in said blow mold and displaceable upon engagement with a choke in the neck, means for directing air from a source to the parison to be blown in said blow mold, and means controlled by the position of said gauge for admitting blowing air to said blow mold.
2. In a bottle blowing machine, the combination of a blow mold in which a parison of glass with a substantially completely formed neck finish is received for final blowing, a blow head, a gauge movable through said blow head and into said blow mold and normally connecting a source of blow air to said blow mold, and means controlled by displacement of said gauge for controlling the supply of blow air to said blow head.
3. In a bottle blowing machine, the combination of a blow mold in which a parison of glass with a substantially completely formed neck finish is received for final blowing, means for gauging the neck of a parison received in said blow mold, said means being normally movable into the neck of the parison to be blown in said blow mold but displaceable upon engagement with a choke in the neck, and means for interrupting the supply of blow air to the blow mold when said gauging means is displaced.
4. In a bottle blowing machine, the combination of a blow mold in which a parison of glass with a substantially completely formed neck finish is received for final blowing, a blow head, means for gauging the neck of a parison received in said blow mold, said gauge being normally movable into the neck of a properly formed parison but displaceable upon engagement with a choke in the neck, and means for controlling the flow of blow air to said blow mold responsive to the position of said gauge.
5. In a bottle blowing machine, the combination of a blow mold in which a parison of glass with a substantially completely formed neck finish is received for final blowing, a blow head, a tube movable through said head and having a passageway for the communication of blowing air to said blow mold, a gauging end on said tube normally movable into the neck of a properly formed parison but displaceable upon engagement with a choke in the neck, and means for supplying blow air to said tube only when said gauging end is in normal position.
6. In a bottle blowing machine, the combination of a blow mold in which a parison of glass with a substantially completely formed neck finish is received for final blowing, a blow head, a tube reciprocable in said blow head and having a passageway for the communication of blow air to said blow mold, a gauging end on said tube normally movable into the neck of a properly formed parison received in said blow mold but displaceable upon engagement with a choke in the neck, a piston on said tube, a cylinder head in which said piston is movable, the passageway in the tube being in communication with said cylinder head, and means for communicating blow air to said cylinder head above said piston when said gauging end is in normal position.

7. In a bottle blowing machine, the combination of a blow mold in which a parison of glass with a substantially completely formed neck finish is received for final blowing, means for communicating blow air from a source to said blow mold, a cylinder head in communication with said means, a piston movable in said cylinder head, means associated with said piston for gauging a parison disposed in said blow mold, said gauging means being effective for displacing said piston in said cylinder upon engagement with a choke in the neck of a parison disposed in said blow mold, said cylinder head being provided with an exhaust port through which air from said source may be exhausted upon displacement of said piston.
8. In a bottle blowing machine, the combination of a blow mold in which a parison of glass with a substantially completely formed neck finish is received for final blowing, a blow head, a cylinder head, a tube communicating with said cylinder head and said blow mold, said tube having a gauging end normally movable to a position within the neck of a parison received in said blow mold but displaceable upon engagement with a choke in the neck, a piston on the opposite end of said tube movable within said cylinder head, means for communicating blow air into said cylinder head above said piston and into said tube when said gauging end is in its normal position within the neck of a parison to be blown and for exhausting said air when said piston is displaced by engagement with a choke in the neck of the parison in the blow mold.
9. In a bottle blowing machine, the combination of a blow mold in which a parison of glass with a substantially completely formed neck finish is received for final blowing, a blow head, a blow head holder, a tube extending through said holder and said head and into said mold, a gauge on one end of said tube, normally movable into the neck of a properly formed parison received in said blow mold but displaceable upon engagement with a choke in the neck, and a piston on the other end, a cylinder head, said cylinder head having inlet and exhaust ports, said piston being movable in said cylinder head to selectively connect said inlet port with said tube and with said exhaust port to supply blow air to said blow mold when the piston is in one position by reason of the free passage of said gauge into a parison having a properly formed neck finish and to exhaust the blow air when the piston is in another position by reason of engagement of said gauge with a choke in the neck of an improperly formed blank.
10. In a bottle blowing machine, the combination of a blow mold in which a parison of glass with a substantially completely formed neck finish is received for final blowing, a gauge movable to a position within the neck of a parison received in said blow mold and displaceable upon engagement with a choke in the neck, means for directing air from a source to the parison to be blown in said blow mold, an electrical valve for controlling the flow of air from said source, and means controlled by the position of said gauge for energizing said valve.
11. In a bottle blowing machine, the combination of a blow mold in which a parison of glass with a substantially completely formed neck finish is received for final blowing, a blow head, a gauge movable through said blow head and into said blow mold, means for directing air from a source to the parison to be blown in said blow mold, a cylinder head in communication with said means, a piston movable in said cylinder head, means associated with said piston for gauging a parison disposed in said blow mold, said gauging means being effective for displacing said piston in said cylinder upon engagement with a choke in the neck of a parison disposed in said blow mold, said cylinder head being provided with an exhaust port through which air from said source may be exhausted upon displacement of said piston.
12. In a bottle blowing machine, the combination of a blow mold in which a blank of glass with a substantially completely formed neck finish is received for final blowing, a blow head, a gauge movable through said blow head and into position within the neck of a parison received in said blow mold and displaceable upon engagement with a choke in the neck, means for directing air from a source to the parison to be blown in said blow mold, a control valve for said means, electrical means for opening said control valve, and means for connecting said electrical means to a source of current supply only when said gauge means is in its normal position.
13. In a bottle blowing machine, the combination of a blow mold in which a parison of glass with a substantially completely formed neck finish is received for final blowing, a blow head, a cylinder head, a tube communicating with said cylinder head and said blow mold, said tube having a gauging end normally movable to a position within the neck of a parison received in said blow mold but displaceable upon engagement with a choke in the neck, a piston on the opposite end of said tube movable within said cylinder head, means for communicating blow air into said cylinder head above said piston and into said tube when said gauging end is in its normal position within a parison to be blown, a valve for said air supply means, electrical control means for said valve, and means for connecting said electrical control means with a current source when said gauging end is in its normal position within the neck of a blank to be blown.
14. In a bottle blowing machine, the combination of a blow mold in which a parison of glass with a substantially completely formed neck finish is received for final blowing, a blow head, a tube reciprocable in said blow head and having a passageway for the communication of blow air to said blow head at a point above the lip of the parison in said blow mold, a gauging end on said tube normally movable into the neck of a properly formed parison received in said blow mold but displaceable upon engagement with a choke in the neck, said gauging end being normally movable into the neck of a properly formed parison but displaceable upon engagement with a choke in the neck, and means for controlling the flow of blow air to said blow head responsive to the position of said gauge.
15. In a bottle blowing machine, the combination of a blow mold in which a parison of glass with a substantially completely formed neck finish is received for final blowing, a gauge normally movable to a position within the neck of a parison received in said blow mold and displaceable upon engagement with a choke in the neck, means effective only when said gauge is received within the neck of a parison for directing air from a source to the parison to be blown at a point above the lip thereof, whereby the air must travel between the inner neck surface and the gauge and any minor choke in the neck will be blown out.
